UNITED STATES PATENT OFFICE.

GEORGE A. TAFF, OF COLORADO SPRINGS, COLORADO.

APPARATUS FOR EXTRACTING PETROLEUM FROM SHALE AND OTHER MINERALS.

Application filed February 14, 1921. Serial No. 444,938.

To all whom it may concern:

Be it known that I, GEORGE A. TAFF, a citizen of the United States, and resident of Colorado Springs, in the county of El Paso 5 and State of Colorado, have invented new and useful Improvements in Apparatus for Extracting Petroleum from Shale and Other Minerals, of which the following is a description, reference being had to the accompanying drawings, which are a part of this 10 specification.

The invention relates to apparatus for extracting the volatile constituents, including hydrocarbons, from oil bearing rock or 15 shale.

Formerly it has been the practice to roast a mass of the crushed oil shale in a retort to drive off the volatile constituents, including hydrocarbons, but such a method has been 20 found to be unsatisfactory when handling shales of the character found in the western part of our country, as the amount of petroleum extracted is small and generally of inferior quality. I have discovered that 25 by agitating the crushed shale while in a retort so that all the particles of shale are constantly being exposed to the heated surfaces of the retort and by keeping up this agitation of the shale during its passage 30 through the retort a much greater yield of petroleum may be obtained from the rock than has heretofore been possible. Furthermore, by employing such a method the petroleum content may be extracted from the 35 shale during its progress through the retort and large quantities thereof handled in an efficient manner, thereby putting the manufacture of petroleum from oil shale upon a commercially practicable basis.

40 The object of the invention is to provide an apparatus for carrying my method into effect, in which the raw oil shale is introduced into a heated retort and continually agitated as it is carried therethrough, the 45 volatile constituents, including the hydrocarbon, passing off as gas or vapor and the residue being ejected from the retort after a sufficient length of time to accomplish the thorough decomposition of the raw material.

50 This invention further consists in the apparatus for extracting the petroleum content of oil-bearing rock as hereinafter set forth and more particularly defined by claims at the conclusion hereof.

55 In the drawings: Fig. 1 is a vertical sectional view through an apparatus embody-

ing the invention and for use in carrying out the method; Fig. 2 is a detail sectional view taken on the line 2—2 of Fig. 1; Fig. 3 is a detail side view of the retort; Fig. 4 60 is a section taken on the line 4—4 of Fig. 1; Fig. 5 is a detail plan view of the impeller; Fig. 6 is a detail sectional view of Fig. 5.

My method consists in heating the finely crushed oil-bearing rock while the same is 65 being agitated. More particularly the agitation of the material is accomplished by conveying it through a heated retort in a stream which is being constantly agitated to cause the material to be turned over and 70 over during the heating operation.

A retort 7 extends for a greater portion of its length within a combustion chamber 8 enclosed by walls 9 of firebrick or other refractory material, the end portions of the 75 retort being supported upon the walls and intervening piers of this brick structure and projecting beyond the same for purposes hereinafter described.

The retort is here shown in the form of a 80 rectangular chamber divided for the greater portion of its length by a centrally disposed combustion chamber 10 into upper and lower muffles 11 of much less height than width and length in order to present a large 85 surface to the hot gases from a furnace 12, here shown as an oil fired furnace. The sides of the retort 7 are provided with ledges 13 and 14 and brick baffles 13' and 14' extending from the outer side walls 9 to these 90 ledges so that the combustion chamber is divided into a lower conduit 15 an intermediate conduit 10' in free communication with the chamber 10, and an upper conduit 16. The baffle 13' stops short of the end 15' of 95 the chamber 10, as shown in Fig. 3, and the baffle 14' in a similar manner stops short of the end 16' of the chamber 10 so that the gases from the furnace 12 pass through the conduit 15, then through the conduit 10' and 100 chamber 10 and through the conduit 16 to the stack 17. In this way the entire surface of the muffles 11 is heated by the hot gases circulated through the space around the muffles.

105 Shafts 18 are mounted in the exposed end portions of the retort and carry sprockets 19 over which the chains 20 of an endless impeller pass. The bearings of the shaft 18 adjacent the stack 17 project through slots 110 21 in the retort and are integral with adjustable bearing plates 22 secured to the

sides of the exposed end portions of the retort over the slots 21. Each plate is provided with a plurality of slots 23 through which clamping bolts 24 pass and tension 5 screws 25 secured to the plates and passing through lugs 26 on the retort are provided with nuts 27 so that the plates with the shaft bearings may be moved to adjust the tension of the impeller chains. The impeller chains 20 have a plurality of flights 28 connected thereto which serve to carry the shale through the muffles 11 and also keep turning it over during its passage therethrough.

15 Each impeller flight consists of a rectangular frame 29 fitting within alined links of the chains 20 and carrying scraper blades 30 which are inclined from the direction of travel with the end of adjacent blades 20 arranged in overlapping relation, the blades of adjacent flights being oppositely inclined, as shown in Fig. 5, so as to cause the material pushed along the muffle 11 by said blades to be constantly shifted laterally in 25 furrows, first toward one side and then toward the other side of these muffles. This provides a very strong and simple flight construction without any moving parts or parts that have to be specially fitted to 30 shafts or the like. Thus, while the material is being moved through the muffles its direction is constantly changing and producing a thorough agitation and turning over of the material so as to bring all portions 35 thereof into contact with the heated surfaces of the retort, and the blades also prevent the material sticking to or becoming lodged in the retort.

40 The finely crushed raw oil shale or oil-bearing rock is introduced into a hopper 31 and fed to a rotating self-sealing measuring valve 32 provided with radially disposed pockets 33 from which the material is discharged into the entrance 34 of the 45 upper muffle 11. A table 35 is provided adjacent this entrance to prevent material falling through this end of the retort and cooperating with the impeller flights as they leave the sprockets at this end of the machine to assist them in starting the material 50 on its travel through the retort. The material is carried by the impellers along the bottom of the upper muffle and falls off the rear end of said muffle and is then carried along the bottom of the lower muffle 55 and finally, when the volatile constituents have been driven off, the residue is ejected into a discharge hopper 36 having a rotating self-sealing discharge valve 37 similar to the 60 valve 32. The volatile hydrocarbon constituents pass from the retort through a

pipe 7" and are subsequently treated to extract or separate the petroleum therefrom. Both the valves 32 and 37 are driven from any suitable source of power, as by a driven 65 chain 38 passing around the sprocket 39 carried by each of the valves, only one being shown in detail, and the shaft 18 at the entrance end of the machine is driven in a similar manner by a driven chain 40 passing 70 around a sprocket 41 on said shaft.

From the foregoing it will be noted that the raw rock is kept in a constant state of agitation during its passage through the retort and by the time it reaches the 75 discharge end of the retort it has been relieved of its volatile hydrocarbon constituents. The rate of rotation of the feed valve 32 and the speed of the impeller are preferably such as to maintain a shallow moving 80 bed of material upon the floor of the muffles 11.

What I claim as my invention is:

1. An apparatus for extracting hydrocarbon constituents from oil shale or other 85 minerals comprising a heating chamber, a sealed retort having separated upper and lower muffle portions extending through said chamber and end portions communicating with said muffles exterior of said chamber, conveyor drive elements mounted in said end portions, one of said end portions including longitudinally adjustable plates supporting one of said conveyor drive elements, an endless agitating conveyor running over said elements and through said muffles, means exterior of the retort for adjusting said plates to adjust the tension of the conveyor, means for delivering the finely crushed oil shale or other mineral to 90 one end of one of said muffles, a discharge passage for the residue communicating with the same end of the other muffle, and means for conducting the volatile constituents of the oil shale or other mineral from the 95 retort.

2. In an apparatus for extracting hydrocarbon constituents from oil shale or other minerals comprising a retort having a muffle, an agitating conveyor running through said muffle including spaced chains, rectangular frames mounted in alined links of said chains, and inclined agitator blades secured to the sides of each frame and projecting below said frame.

In testimony whereof, I affix my signature, in presence of two witnesses.

GEORGE A. TAFF.
